UNITED STATES PATENT OFFICE.

WILLIAM HEYWOOD MOTTERSHALL, OF THORNHILL, ONTARIO, CANADA.

VENTILATION SYSTEM.

Application filed August 16, 1923. Serial No. 657,821.

To all whom it may concern:

Be it known that I, WILLIAM HEYWOOD MOTTERSHALL, a subject of the King of Great Britain, and a resident of the village of 5 Thornhill, in the county of York, in the Province of Ontario, Canada, have invented certain new and useful Improvements in Ventilation Systems, of which the following is the specification.

10 My invention relates to improvements in ventilation systems and the object of the invention is to devise means whereby the vitiated air in buildings and other structures will be more readily removed than is the 15 case at present.

A further object is to devise means for increasing the velocity of the vitiated air due to its being increased in density whereby the suction into the ventilating shaft is increased with the consequent increase in the 20 velocity of the up current of air.

A still further object is to devise an improved means of ventilation equally applicable to buildings, automobiles, steamboats, 25 railways and all closed vehicles.

My invention consists of a ventilation system constructed and arranged all as hereinafter more particularly described and illustrated in the accompanying drawing in 30 which:

Fig. 1 represents a vertical section through a building showing my system applied thereto.

Fig. 2 is a longitudinal section through two of the horizontal spaced apart cones used in my system, and

Fig. 3 is a cross sectional view through the line 4—4 Figure 2.

Like characters of reference indicate corresponding parts in the different views.

1 are the walls of the building. 2 are the ceilings of the respective floors. 3 is the vertical ventilating shaft extending down through the building and up through the roof thereof, said shaft 3, if desired, being provided at its top with a revolving cowl of the type set forth in my United States Patent #1,528,683 issued March 3, 1925, or of any standard type.

50 In my construction I dispose my spaced apart cones in three distinct ways. For example, on any floor I may provide a horizontal branch shaft 5 from which depends the hollow conical member 6 communicating therewith and into which is inserted the

cylindrical shank 7 of the hollow conical member 8, said shank being of less diameter than the neck of the member 6 and consequently being spaced therefrom. Below the hollow conical member 8 I provide a funnel shaped member 9 with its flared mouth directed downwardly, the outlet 10 of said member 9 being of less diameter than the diameter of the cylindrical shank 7 of the hollow conical member 8 into which it is inserted, and into the inlet end of the funnel shaped member 9 I insert the hollow conical member 11, its outlet again being of less diameter than the neck of the funnel shaped member 9, such hollow conical member 11 being so disposed that its larger end is lowermost.

The members 6, 8, 9 and 11 are disposed vertically and are particularly adapted to be set over machines, cooking ranges and in other positions in a room where it is desired to remove foul air. In the drawing one set of these members 6, 8, 9 and 11 is provided at the bottom of the shaft 3, but it is to be understood that they will be equally effective if depending from branch shafts connected to such vertical shaft, both constructions being illustrated in Figure 1 of the drawing.

For general ventilation purposes in a building I provide a series of double hollow conical members 12 of funnel shape, as is clearly illustrated in Figure 1, said members being secured by hangers 13 in spaced relation to each other so that their longitudinal axes are substantially horizontal, the necks 14 of each member inserted into the air inlet end of the next hollow conical member.

In constructing the conical members 12 I preferably provide an adjustable central portion as illustrated in Figure 3 wherein the cylindrical end 15 of the neck portion is adapted to telescope into a cylindrical portion 16 in the skirt portion, thus permitting of the necessary adjustment in length of these two portions of each member, the neck portion of each member being provided with radially extending webs 17 with turned over feet 18 adapted to engage the interior of the skirt of the next conical member.

When the system is installed, a portion of 105 the vitiated air entering the lower cone 11 is increased in density with the consequent increase in velocity and thus as it is expelled into the second conical member 9 a suction is created on the air that is being 110

introduced into such conical member 9, which as it passes upwardly again increases in velocity owing to its increase in density as it is discharged into the member 10 from the smaller end of such member 9. Thus a suction is created on the air introduced directly through the member 6 and the up current of air is increased prior to introduction into the transverse shaft 5 and the vertical shaft 3.

In the case of the horizontally disposed conical member 12 the vitiated air in the room passes into each member 12 and as it passes therethrough, it increases in density with the consequent increase in velocity, thus creating an increased suction on the air introduced into the next member 12.

Owing to the adjustability of the neck and skirt portions of the members 12 it will be seen that the amount of air introduced into a member can be controlled as desired, depending upon the particular conditions in the room.

From the above description it will be seen that I have devised a simple and effective ventilating system which can be readily installed and which will materially increase the efficiency of ventilating or chimney shafts.

It is to be understood that the horizon-

tally disposed cones and the vertically disposed cones in the room, can be used in conjunction with each other, or may be used separately if desired, depending upon the ventilation necessary in the building.

35

What I claim as my invention is:

1. In ventilation systems, a plurality of spaced apart funnel shaped members, each comprising a neck portion and a coacting skirt portion, such portions longitudinally 40 adjustable with respect to each other, each neck portion inserted into the skirt portion of the next member, such neck being of substantially less diameter than the diameter of such skirt portion, and means for holding the necks in their centred position in the skirt portions.

2. In ventilation systems, a plurality of spaced apart funnel shaped members, each comprising a neck portion and a coacting 50 skirt portion, such portions longitudinally adjustable with respect to each other, each neck portion inserted into the skirt portion of the next member, such neck being of substantially less diameter than the diameter of 55 such skirt portion, and a plurality of outwardly extending webs secured to each neck and adapted to engage the interior of each skirt portion.

WILLIAM HEYWOOD MOTTERSHALL.
